OVERSHOE

Rena Bell Hardman, Los Angeles, Calif.

Application August 10, 1950, Serial No. 11,705

Term of patent 14 years

(Cl. D7—4)

To all whom it may concern:

Be it known that I, Rena Bell Hardman, a citizen of the United States of America, residing in the city of Los Angeles, in the county of Los Angeles, State of California, have invented a new, original, and ornamental Design for an Overshoe, of which the following is a specification, reference being had to the accompanying drawing, forming a part thereof.

Fig. 1 is a front perspective view of an overshoe in closed position, as in use, showing my new design;

Fig. 2 is a front perspective view of the overshoe in open position;

Fig. 3 is a top plan view of the overshoe in closed position; and

Fig. 4 is a partial cross-section taken at 4—4 in Fig. 3.

I claim:

The ornamental design for an overshoe, substantially as shown and described.

RENA BELL HARDMAN.
